OIL TANK AND METHOD OF STORING OIL

Application filed September 12, 1927. Serial No. 218,995.

This invention relates to oil tanks and particularly to tanks designed for storing oil, either crude or refined, in considerable quantities. The invention further relates to methods of sealing oil in tanks to safeguard the oil against evaporation and ignition, while providing for its volumetric changes due to expansion and contraction, or other causes.

10 It is well known in the oil industry that enormous losses result from evaporation of stored oil, primarily during storage of the oil in large tanks at the oil fields, refineries, or distribution centers. Efforts have been 15 directed along various lines toward elimination or reduction of such losses but no complete solution of the problem has been heretofore achieved.

It is an object of the present invention 20 to so improve the tanks employed for quantity storage of oil as to completely eliminate all evaporation losses.

In attaining this object, the invention contemplates extending a water-filled trough 25 within and around the upper portion of an oil tank, and extending freely into said trough an annular flange marginally formed upon a cover for the tank.

The invention further contemplates es- 30 tablishing a liquid-full condition beneath said cover by maintaining a sufficient depth of water beneath the oil to raise the latter to the level of the cover.

It is an additional object of the invention, 35 to provide an oil outlet beneath and adjacent to said cover and to provide means for preventing any delivery to said outlet of water discharging over the edge of said trough.

40 The above and various other objects the invention attains by the construction herein-after described and illustrated in the accompanying drawings, wherein:

45 Figure 1 is a vertical sectional view of the improved tank, showing the cover in its normal position seating upon the trough, the illustrated levels of oil and water being such as to balance the hydrostatic pressures of 50 a layer of water upon the cover and of a

small quantity of oil rising in the gauge well carried by the cover.

Figure 2 is a fragmentary sectional view of the upper portion of the tank showing the conditions prevailing when the weight 55 of the cover as well as the pressure of a layer of water thereupon are counter-balanced by the oil.

Figure 3 is a view similar to Figure 2 but showing the conditions prevailing when 60 sufficient oil has been introduced in the tank to raise the cover some distance.

In these views the reference character 1 designates an oil tank which may be formed of sheet steel or other suitable metal, as is 65 common practice. Ordinarily this tank will be cylindrical and open-topped and proportioned to store a large quantity of oil.

Interiorly mounted upon the upper portion of the tank 1 is an annular plate 2, the 70 vertical dimension of which may approximate three feet. Said plate is spaced several inches from the tank wall, and has its lower portion out-turned and secured to said wall, forming with the latter an annular open- 75 topped trough 4 of considerable depth as compared to its radial dimension or width. The top of said trough is located some distance (as for example eighteen inches) below the upper edge of the tank. Above said 80 trough a vertically adjustable cover 5 extends substantially fully across the tank and a flange 6 rigidly carried by said cover at its margin depends into said trough and is vertically dimensioned to closely approach or 85 engage the bottom of the trough when said cover lies close to or engages the trough wall 2. The cover 5 is preferably flat or nearly so and may be formed of sheet iron or the like, reinforced if desired, in any suitable 90 manner (not shown).

Suitably carried by said cover, preferably near the margin thereof, is a tubular gauge well 7 opening at its lower end through the cover and rising above the latter a suitable 95 distance, as for example, several feet. The upper end of said gauge well is provided with a cover 8 which preferably has a marginal depending flange 9 freely engaging in an annular trough 10 carried by the upper 100

end of said well. A pipe 11 communicating with the upper portion of said well is downturned within the tank and opens at its lower end adjacent to the cover 5. Said pipe carries, preferably upon its upper portion, a pair of fittings 12 and 13 providing respectively for the inflow of air to said well and its outflow therefrom.

An oil delivery pipe 14 enters the lower portion of the tank, passing preferably through the side wall thereof, and is valved as indicated at 15 exteriorly of the tank. Branching from the pipe 14 at the supply side of the valve 15 is an oil discharge pipe 16 which passes through the tank wall and rises within the tank to terminate in the top portion thereof in a bell-shaped inlet 17. Said inlet is preferably positioned to have a slight clearance from the cover 5 when the latter is in its lowermost or normal position, (see Figure 1). A valve 18 suitably located in the pipe 16 controls the out-flow of oil therefrom.

Water from any suitable source of supply is adapted to be delivered into the tank adjacent to the bottom thereof through a pipe 19, and a branch 20 from said pipe rises exteriorly of the tank and extends across the edge of the latter to provide for a discharge 25 of water upon the cover 5. A three-way valve 21 is arranged at the juncture of the pipes 19 and 20 to selectively control the delivery of water to the lower portion of the tank or upon the cover 5.

It is preferred to provide within the tank 30 an annular curtain 22 suspended from the cover 5 and spaced slightly inwardly from the plate 2. Said curtain may be formed of a closely woven fabric or other suitable sheet material and extends downwardly a 35 distance preferably from ten to fifteen feet. If desired a valved outlet 23 may connect with the top portion of the tank through the side wall thereof providing for withdrawal 40 of water from above the cover 5 and it may also be desirable to provide a valved fitting 45 opening from the bottom of the trough 4 as a provision for washing out any accumulation of sediment. It is optional furthermore 50 in practicing the invention to provide a spill-way 25 at the upper edge of the tank.

It may be necessary, in applying the invention to tanks of quite large diameter to provide means within the tank for supporting the central portion of the cover, at such times as this function is not exercised by the liquid below the cover. Thus pillars 26 may rise at suitable points from the tank bottom to terminate at their upper ends substantially 55 at the level of the upper edge of the plate 2.

In use of the described construction, water is pumped through the pipe 19 to form the usual water cushion 27 in the bottom portion of the tank, and oil is then pumped in through 60 the pipe 14, preferably to some lower level

than that of the cover. Water is now delivered through the pipe 20 on top of the cover member from which it discharges into the trough 4 filling the latter and overflowing therefrom to fall through the oil and add itself to the water cushion supporting the oil. Thus the oil level is raised, and eventually rises into the gauge well 7, thereby rapidly building up a liquid-static pressure in the entire body of oil, until this pressure becomes adequate to stop the flow of water across the upper edge of the annular plate 2. After this occurs, water can be accumulated upon the cover 5, and this accumulation is preferably continued to a depth of at least 65 several inches. A trivial quantity of additional water will discharge from the trough, due to the accumulation of water upon the cover and will further slightly raise the oil level in the gauge well to balance. 75

The tank is now in readiness for storage of its oil content for any desired period of time positively without loss by evaporation. The prevention of evaporation necessarily follows from the liquid-full condition of the tank and from the fact that a protective layer of water lies always above the cover 5 and within the trough 4 forming a seal against access of air to the oil. The only attention required to continuously avoid all evaporation is that 80 necessary to maintain some depth of water upon the cover 5, since this water will of course, gradually evaporate and will furthermore, when the cover 5 rests upon its bearings, discharge through the trough into the 85 bottom portion of the tank to such extent as the oil undergoes shrinkage or is withdrawn from the tank. 95

When it is desired to withdraw oil from the tank, the valve 18 is opened, permitting such 100 outflow as may be desired through the pipe 16. It is preferred to compensate for any withdrawal of oil by pumping upon the cover 5 a corresponding quantity of water, thus 105 maintaining a liquid-full condition. It is, however, feasible to temporarily operate the tank on a part-full basis, flowing the oil in and out by way of the pipe 14 as in the present 110 practice. Under these conditions, the water in the trough 4 still forms a liquid seal, but a slight evaporation may occur by saturation of such air as accumulates below the cover. Any 115 vacuum tendency resulting from falling of the oil level below the cover 5, when operating on a part full basis is overcome by air admitted at 12 to the gauge well, also by air admitted by the pipe 11 now free and open by absence of water above the cover 5. 120

Subsequent to balancing the oil and water 125 pressures against each other on initial filling of the tank, as hereinbefore described, any volumetric increase in the tank contents, whether due to thermal expansion or an addition of oil or cushioning water, will find relief by a flow of oil into the trough 4. The 130

- level of water in said trough, inwardly of the flange 6, will consequently be lowered, the water so displaced effecting a slight increase in depth of the water upon the cover. 5 As the volumetric increase continues and the annular meeting plane of oil and water progressively lowers in the trough, there is gradually built up in the oil a liquid static pressure, due to the difference in densities of the 10 contacting bodies of water and oil. This gradually rising internal pressure in the oil body is productive of and accompanied by a corresponding rise of oil in the gauge well 7. Eventually, internal (or liquid static) 15 pressure of the oil reaches a magnitude such that its upwardly acting component equalizes the weight of the cover.

When the conditions above described are fulfilled any further expansion of the tank 20 contents acts to lift the cover 5. Such lifting however, does not involve any appreciable increase in the liquid pressure acting thereagainst, since the upward movement of cover 5 is responsive to a pressure only slightly exceeding the weight of the metal comprising said cover.

When the cover 5 is lifted as described the pressure of water in the trough at the outer side of the flange 6 and that of the oil in said 25 trough at the inner side of said flange remain equalized. Any disparity in the pressures at opposite sides of said flange will cause the dividing line between the water and oil to gradually move in continuous automatic balance. The depth of the trough and that of the flange 6 on the cover 5 are sufficient to 35 keep the dividing line within the trough 4 under all expected operating conditions.

If through carelessness, cumulative expansion 40 were allowed to so lift cover 5 as to raise the dividing line above the top of the trough 4, then all water above the cover 5 will flow through the trough 4 to fall to the tank bottom. After such flow of water a balance of 45 pressures between the thereby reduced water pressure and increased oil pressure will instantly attain. To correct this condition water may be withdrawn from the tank bottom and replenished upon the cover 5.

50 The term oil as herein employed, is considered inclusive of any liquid petroleum product.

At times when cumulative expansion of the tank contents has lifted the cover 5 off its 55 bearings the relatively small daily change in oil volume (by thermal cause) will relatively move the cover 5 vertically without appreciable movement of the liquid within the trough 4. At the lifting of the cover 5 the 60 vertical column of water between the flange 6 and the tank wall 1 is correspondingly elongated to maintain a pressure in balance with the oil head in the gauge well 7.

The condition may sometimes arise that 65 volumetric decrease of the oil body, resulting

either from thermal contraction or withdrawals, may not only permit the cover to seat upon the pillars 26 but may tend to lower the oil-level clear of the cover. It is to be noted that such lowering of the oil level will not be permitted so long as sufficient water remains in the trough to discharge downwardly through the oil and compensate for the oil shrinkage or withdrawals by the resulting increase in the volume of cushioning water below the oil. 70

While it will be apparent that the illustrated embodiment of my invention herein disclosed are well calculated to adequately fulfil the objects and advantages primarily stated, it is to be understood that the invention is susceptible to variation, modification and change within the spirit and scope of the subjoined claims. 80

What I claim is:

1. In a device of the character described, the combination with an open-topped oil storage tank, of a trough extending interiorly upon and around the upper portion of said tank for receiving a sealing volume of water, a vertically movable cover member disposed within the tank above said trough provided with a marginal depending flange freely engaging in said trough, means for discharging water into the tank upon said cover member, an oil discharge pipe having its inlet disposed slightly below the normal level of said cover member, and means within said tank prohibiting a direct flow of water from said trough to the inlet of said discharge pipe. 85

2. In a device of the character described, the combination with an open-topped oil storage tank, of a trough for receiving a sealing volume of water extending interiorly upon and around the upper portion of said tank, a vertically movable cover member disposed within the tank above said trough and provided with a depending marginal flange freely engaging in the trough, means for delivering oil into the tank below the cover member, a discharge pipe for oil having its inlet arranged within the tank slightly below the normal level of the cover member, and an annular curtain carried by and depending from the cover member between the trough 100 and said inlet. 105

3. In a device of the character described, the combination with an open-topped oil storage tank, of a trough for receiving a sealing volume of water extending interiorly 120 upon and around the tank at a distance below the upper edge of the tank, a vertically movable cover member for the tank arranged above said trough and provided with a marginal depending flange freely engaging in said trough, means carried by the tank for discharging water therein above said cover member, means for withdrawing oil from the tank at a level below and adjacent to said cover member, and a tubular member rising 125

from said cover and opening at its lower extremity through the cover.

4. In a device of the character described, the combination with an open-topped oil storage tank, of a trough extending interiorly upon and around the upper portion of said tank for receiving a sealing volume of water, a vertically movable cover member disposed within the tank above said trough provided 5 with a marginal depending flange freely engaging in said trough, means for discharging water into the tank upon said cover member, an oil discharge pipe having its inlet disposed slightly below the normal level of said cover 10 member, means within said tank prohibiting a direct flow of water from said trough to the inlet of said discharge pipe, and a tubular member rising from said cover and opening at its lower extremity through the cover.
- 15 5. In a device of the character described, the combination with an open-topped oil storage tank, of a trough for receiving a sealing volume of water extending interiorly upon and around the upper portion of said 20 tank, a vertically movable cover member disposed within the tank above said trough and provided with a depending marginal flange freely engaging in the trough, means for delivering oil into the tank below the cover member, a discharge pipe for oil having its 25 inlet arranged within the tank slightly below the normal level of the cover member, an annular curtain carried by and depending from the cover member between the trough and said 30 inlet, and a tubular member rising from said cover and opening at its lower extremity through the cover.
- 35 6. The combination with an oil storage tank, of a cover member for the contents of 40 said tank, of non-buoyant construction and of a material exceeding in weight its displaced volume of oil disposed within said tank and vertically movable to compensate for volumetric changes in the contents of the 45 tank, means within the tank for supporting said cover member in a lowermost position thereof, means for introducing oil into the tank below said cover member, means for introducing water into said tank above said 50 cover member, and means for opposing the liquid-static pressures of the water and oil, marginally of said cover member, to effect a building up of the liquid-static pressure of the oil, and a consequent raising of the cover 55 member upon a predetermined volumetric increase of the oil.

7. The combination with an open-topped oil storage tank, of a cover member therefor freely vertically movable within said tank 60 and marginally formed with a depending annular flange, an annular trough interiorly carried by said tank below its upper edge, and receiving said flange, means within the tank, other than said trough for supporting 65 said cover member in a lowermost position

thereof, means for introducing oil into the tank below said cover member, whereby upon a rise of such oil to the lowermost level of said cover member, it enters the trough between said flange and the inner wall of the 70 trough, and means for delivering water upon said cover member and thence into said trough, whereby the liquid-static pressures of the oil and water are opposed in said trough to compel a raising or lowering of 75 the cover responsive to a volumetric increase or decrease in the oil.

8. The method of sealing a body of oil within a tank against evaporation, and of providing for volumetric changes in said 80 body, consisting in engaging the surface of said body by a freely vertically movable cover member, maintaining a body of water upon and around said cover member, and so confining a portion of said water and a portion of said oil beneath the marginal portion of the cover as to oppose a downward liquid static pressure of the oil to an upward liquid static pressure of the water.

9. The method of sealing a body of oil 90 against evaporation within a tank, and of providing for volumetric changes in said body consisting in engaging the surface of said body by a freely vertically movable cover member, maintaining an annular body of 95 water surrounding said cover member, and so confining a portion of said water and a portion of said oil beneath the marginal portion of the cover as to oppose a downward liquid static pressure of the oil to an upward 10 liquid static pressure of the water.

10. The method of storing a body of oil in a tank, consisting in engaging the top surface of said body by a freely vertically movable cover member, maintaining a cushion of 10 water within the tank beneath the oil, interposing between the cover and the tank wall a sealing body of water separate from said water cushion and elevated above the latter, and counterbalancing said cover through the 11 medium of said oil by the weight of said surrounding water body.

11. A method of sealing a body of oil within a tank against evaporation, and of providing for volumetric changes in said body consisting in engaging the surface of said body by a freely vertically movable cover member maintaining a body of water in surrounding relation to said cover member, confining a portion of said water and a portion of said 12 oil beneath the marginal portion of the cover so as to oppose a downward liquid static pressure of the oil to an upward liquid static pressure of the water, and elevating a relatively small portion of the main oil body 12 sufficiently above said cover member to create in the main body of oil an internal pressure counterbalancing by its upwardly acting component the weight of said cover.

12. A method of sealing a body of oil 13

against evaporation within a tank, and providing for volumetric changes in said body consisting in engaging the surface of said body by a freely vertically movable cover member, supporting a body of water in surrounding relation to the cover, independently of and upwardly remote from the tank bottom, and opposing the liquid static pressure of said water to that of the oil to counterbalance the cover and effect a raising thereof responsive to volumetric increase of the oil body.

13. The method of sealing a body of oil within a tank against evaporation, and of providing for volumetric changes in said body consisting in engaging the surface of said body by a freely vertically movable cover member, maintaining an annular body of water surrounding the cover member, superposing an annular water blanket upon the cover member and upon said annular body of water, and applying to said body of oil the joint hydrostatic pressure of said annular water body and of the superposed blanket to counterbalance the weight of said cover.

14. The method of sealing a body of oil within a tank against evaporation, and of providing for volumetric changes in said body consisting in engaging the surface of said body by a freely vertically movable cover member, marginally carrying a depending annular flange, segregating an annular portion of oil from said oil body inwardly of said flange, maintaining an annular water body in part outward of said flange, and in part inward of said flange and below the annular oil body, and subjecting the main oil body to a liquid static pressure transmitted from said water body through said segregated portion of oil to the main oil body to counterbalance the weight of said cover.

15. In a device of the character described, the combination with an oil storage tank, of a cover member for said tank marginally formed with an annular depending flange, a trough carried by the upper portion of the tank freely receiving said flange, and adapted to further receive a sealing body of water, means below said cover member for delivering oil to or withdrawing it from the tank, means supporting said cover member in a lowermost position thereof, said cover member being formed with an opening, and a wall surrounding said opening and affording a portion of the oil a rise above the cover member adequate to counterbalance the cover by resulting hydrostatic pressure of the oil.

16. The method of storing a liquid within a tank and safeguarding it against evaporation consisting in applying a cover to the top surface of said liquid, maintaining a sealing body of a more dense liquid between said cover and the wall of said tank, segregating

a relatively small body of the lighter liquid from the main body thereof, in close proximity to said cover, and applying the gravity-induced liquid-static pressure of the heavier liquid to said main body through the segregated portion of said stored liquid.

17. The method of storing a body of oil within a tank, consisting in engaging said body by a freely vertically movable cover member, maintaining a cushioning body of water within the tank beneath the oil, maintaining another and relatively raised body of water adjacent to the cover member within the tank, isolated from said cushioning body, limiting down travel of the cover, and discharging water from said raised water body to said cushioning water body through the oil to maintain contact of the oil body with the cover, responsive to a volumetric decrease of the oil body, when the cover is in its lower limiting position.

In testimony whereof I sign this specification.

EDWIN M. CLARK.
